JEWELRY CASE LOCK

Charles S. Gehrie, Montclair, N. J., assignor to Presto
Lock Co., Garfield, N. J., a limited partnership

Application May 22, 1958, Serial No. 51,021

Term of patent 14 years

(Cl. D50—2)

Fig. 1 is a front view of a jewelry case lock embodying
my design;

Fig. 2 is a top edge view of the same; and
Fig. 3 is a side edge view of the same.

I claim:

The ornamental design for a jewelry case lock, as shown.
